(57) **CLAIM**

The ornamental design for an infrared distance measurement device, as shown and described.

DESCRIPTION

FIG. 1 is a front view of an infrared distance measurement device according to the present application;

FIG. 2 is a rear view of the infrared distance measurement device according to the present application;

FIG. 3 is a left view of the infrared distance measurement device according to the present application;

FIG. 4 is a right view of the infrared distance measurement device according to the present application;

FIG. 5 is a top view of the infrared distance measurement device according to the present application;

FIG. 6 is a bottom view of the infrared distance measurement device according to the present application; and,

FIG. 7 is a perspective view of the infrared distance measurement device according to the present application.
